Primary Examiner — Sheryl Lane*Assistant Examiner* — Ieisha Price(74) *Attorney, Agent, or Firm* — Thompson Hine LLP(57) **CLAIM**

The ornamental design for a folder with flap features, as shown and described.

DESCRIPTION

FIG. 1 is a top view of the folder with flap features; FIG. 2 is a top perspective view of the folder with flap features of FIG. 1; and, FIG. 3 is a perspective view of the folder with flap features of FIG. 2, in a folded and closed condition.

The broken lines in the drawings illustrate portions of the folder with flap features and form no part of the claimed design. The perimeter of folder with flap features, the features shown in full lines and areas rendered with shading are to be understood to be the claimed design. The surfaces without shading are not the claimed design and form no part thereof.
